UNITED STATES PATENT OFFICE.

LOUIS JULLIEN, OF PASSY, FRANCE.

DESIGN FOR A CARPET-PATTERN.

Specification forming part of Design No. 5,921, dated June 11, 1872.

Specification describing a new and original Design for a Carpet, invented by LOUIS JULLIEN, of Passy, in the Department of the Seine, in France.

The accompanying photograph fully illustrates my new design, which consists of a floral scroll with bunches of flowers at the

termini and intersections, and with foliate stems, as shown.

I claim as my invention—

The design for a carpet, as shown.

Witnesses: L. JULLIEN.

F. OLcott,

DAVID I. S. FULLER.
